shorts, which are made of a single thickness of woven fabric material, cut on the bias, and are provided with a front and rear reinforcement, and a front pouch.

UNITED STATES PATENT OFFICE

2,646,572

REINFORCED SHORTS

Fluta H. Eudy, Fairfield, Calif.

Application September 7, 1948, Serial No. 48,032

2 Claims. (Cl. 2—225)

1

This invention relates to garments such as are usually termed "shorts."

It is an object of this invention to provide an improved garment of this character.

It is another object of this invention to provide such a garment having a seamless crotch, and arranged to allow freedom of movement of the wearer, at the same time eliminating sag.

It is another object of this invention to provide a garment of the character described having a bias cut body portion proportioned and arranged in a novel manner to insure a well fitting garment.

It is another object of this invention to provide a garment of the character described arranged in an improved manner to give support to the wearer.

It is another object of this invention to provide a garment of the character described having an improved waist band construction.

This invention possesses many other advantages and has other objects which may be made more easily apparent from a consideration of several embodiments of the invention. For this purpose there are shown a number of forms in the drawings accompanying and forming part of the present specification. These forms will now be described in detail, illustrating the general principles of the invention; but it is to be understood that this detailed description is not to be taken in a limiting sense since the scope of the invention is best defined by the appended claims.

In the drawings:

Figure 1 is a front elevational view of a pair of shorts, incorporating features of the invention;

Figure 2 is a rear elevation thereof;

Figure 3 is a view showing the configuration of one element of the garment of Figure 1;

Figure 4 is a development of the body portion of the garment;

Figures 5 and 6 are detail sectional views, taken substantially as indicated by the correspondingly numbered lines of Figure 1.

Referring to the drawings, the garment shown therein is a pair of men's undershorts, and comprises a body forming portion or member 5 adapted to extend downwardly from the wearer's waist and about the hips to the front portions of the thighs, terminating in spaced upwardly extending edges 6 and 7. The body member 5 is shown as formed of a single thickness of woven fabric material cut on the bias, as indicated by the arrows *a* and *b* in Figure 4, which extend

2

respectively in the direction of the warp and woof of the fabric to provide transverse as well as vertical resilience in the garment. The member 5 has an extension 8 adapted to extend forwardly between the wearer's legs and upwardly in front, terminating in a horizontally extending edge 9 below the waist line. A pair of similar, half panels 10 and 11 are secured respectively to the edges 6 and 7, and to the edge 9, extending upwardly therefrom to the waist line. The half panels 10 and 11 are arranged to be secured releasably in overlapping relation as by a plurality of snap fasteners, buttons or the like, 12, spaced below the waist line, forming when so secured a substantially rectangular panel 13 in the front of the garment.

The half panels 10 and 11 when secured together cooperate to form with the member 5, a body encircling garment. The lower edge of the member 5 cooperating with the opposite edges of the extension 8 to form the thigh openings 14 and 15, for which purpose the extension 8 has a reduced crotch forming portion 8-a.

To maintain the front of the garment against sagging and distortion, the half panels 10 and 11 are arranged to be stretch resistant in a direction transverse of the garment for which purpose they are formed of straight cut fabric, as indicated by the arrows in Figure 3 which extend respectively in the direction of the warp and woof of the fabric. Further, each half panel 10 and 11 may comprise two thicknesses of fabric as shown, formed by folding an appropriately shaped piece of fabric, or by stitching together two pieces.

The bias cut body member 5 is provided with a reinforcement 16 also formed of a single thickness of bias cut woven fabric material of the same or different characteristics from that forming the body member 5. As shown in Figure 4, the reinforcement 16 overlies the crotch forming extension 8 having matching edges therewith, and also has a triangular portion 16-a overlying the body member 5 at the rear of the crotch. The reinforcement 16 is secured to the body member 5 and the extension 8 as by stitching along the edges.

An important feature of the garment is the provision of a supporting pouch 17 at the front of the crotch. This pouch 17 is formed by providing fullness in the extension 8 and reinforcement 16 along the edge 9. Thus, from a comparison of Figure 1 and Figure 4, it will be apparent that in the completed garment the edge 9 extends more or less directly between points X and

Y on the extension 8, a distance substantially less than the distance between these points along the outer edge C of the extension, the edge 9 being spaced from the central or crotch portion of the extension 8. Accordingly, darts or gathers 18 are provided along the edge C to take up the excess material when this edge C becomes the edge 9. Thus, when the extension 8 and reenforcement 16 are joined to the half panels 10 and 11, there is substantial fullness of material along the edge 9 and in the extension and reenforcement therebelow, forming the pouch or pocket 17.

The upper edge portion of the bias cut body member 5 is not sufficiently stretch resistant to provide a satisfactory waist band by itself. Thus, a waist band 20 formed of a piece of straight cut fabric 21 with short pieces of elastic webbing or the like 22 and 23 at the opposite ends thereof is secured as by stitching along the upper edge of the body member 5, terminating respectively at the edges 6 and 7, where the webbing is secured to the half panels 10 and 11 respectively. As clearly shown in Figure 1, the upper end portion of the body member 5 is of sufficient length to permit pleats or gathers indicated at 25 to be formed where it is attached to the elastic webbing 22 and 23, to allow for the stretch of the webbing.

I claim:

1. A pair of shorts comprising: a bias cut body member adapted to extend downwardly from the wearer's waist and about the hips to the front portions of the thighs, and having a crotch forming extension adapted to extend between the legs and upwardly in front to a substantially horizontal edge below the waist; a bias cut reenforcement overlying a part of said body member including said extension, said extension and said reenforcement having matching edges; said reenforcement being secured to said body member and said extension; and means joined to said

horizontal edge extending to the waist, there being darts in said extension and said reenforcement along said edge to provide fullness forming a pouch.

2. A pair of shorts comprising, a body member adapted to extend downwardly from the wearer's waist and about the hips with its ends spaced apart and overlying the front portions of the thighs, said body member having a crotch-forming extension between said ends adapted to extend between the legs and upwardly to an end edge located below the waist, a reinforcement overlying a portion of said body and said extension and secured to said body and said extension, said extension being of reduced width between its ends, said reinforcement being of reduced width between its ends to correspond to the reduced width portion of the extension; the lower edge portions of the body which extend from opposite sides of said extension, as well as the side edges of said extension and side edges of aid reinforcement, extending convergently toward said reduced portions of said extension and said reinforcement, and means forming a garment front joined to said end edge of the extension and to said ends of said body member.

FLUTA H. EUDY.
